UNITED STATES PATENT OFFICE

2,100,180

ELECTRICAL COMMUNICATION CIRCUIT

Stuart Ballantine, Mountain Lakes, N. J., assignee, by mesne assignments, to Radio Corporation of America, New York, N. Y., a corporation of Delaware

Application December 17, 1929, Serial No. 414,797

21 Claims. (Cl. 250—27)

This invention relates to electrical communication circuits and particularly vacuum tube detector circuits.

Objects of the present invention are to provide methods of and circuit arrangements for extending the range over which the audio frequency output voltage of a vacuum tube detector is a substantially linear function of the radio frequency carrier voltage of the input signal. Other objects are to provide methods of and circuits for stabilizing the plate resistance for detection. More specifically, objects of the invention are to provide methods of and circuits for automatically varying the operating characteristics of a vacuum tube detector in accordance with that component of the rectified current in an output circuit of the tube which is due to carrier voltage.

These and other objects of the invention will be apparent from the following specification when taken with the accompanying drawings, in which,

Fig. 1 is a schematic diagram of a detector stage embodying the invention.

Fig. 2 is a curve sheet showing the relation between the plate resistance of detection and the carrier voltage,

Fig. 3 is a curve sheet showing the relation between direct current in the plate circuit and carrier voltage,

Figs. 4 to 9, inclusive, and 11 are circuit diagrams of detector stages embodying the invention, and

Fig. 10 is a circuit diagram of a radio receiver that includes a detector stage constructed in accordance with the invention.

In the circuit shown in Fig. 1, the reference character D indicates a triode vacuum tube having impedance elements and sources of current associated therewith to complete a detector stage in which the tube operates as a plate-circuit rectifier. The input circuit between control grid G and cathode includes an appropriate impedance or terminals across which the signal energy E_0 is impressed, and, if required, a source of current such as battery E_0 for establishing a fixed bias on the grid. The plate circuit of the tube includes a plate current supply source, indicated by battery E_b , and a suitable impedance, such as the primary of the audio frequency transformer T, for transferring the audio frequency output to an amplifier stage, a reproducer or other appropriate load device.

The circuit elements of the detector stage, as so far described, are or may be of any suitable and

appropriate form to constitute a detector stage of the plate-circuit rectifier type.

In accordance with the present invention, the detector stage also includes a circuit element or elements for automatically adjusting the operating characteristics of the tube in accordance with carrier voltage rectified by the tube. As shown in the diagram, the resistance R is a series element in both the plate and the input circuit of the tube, and this resistance is preferably shunted by a condenser C that serves as a filter to repress voltage variations of audio or modulation frequency which, if allowed to enter the grid circuit, would be amplified and in most circumstances, depending upon their phase, would adversely affect the sensitivity of the detector. The usual by-pass condenser C_1 is connected from the plate to cathode to by-pass radio frequency currents around the audio frequency transformer.

The carrier voltage is rectified in the plate circuit and produces a potential drop across the resistance R which increases with carrier voltage. This direct current potential drop is applied to the control grid in such polarity as to increase the grid bias negatively as the carrier voltage increases. The rate at which the automatic bias changes with carrier voltage may be adjusted over a wide range by varying the resistance R.

In my copending application Ser. No. 354,022, filed April 10, 1929, now Patent No. 2,070,640, issued February 16, 1937, I have described the action of this automatic bias in extending the range of carrier voltage throughout which the vacuum tube acts as a linear rectifier, and in the curves comprising Fig. 4 of that application is shown qualitatively the effect obtained when the bias is varied as a function of the carrier voltage.

The automatic variation of the grid bias has another important stabilizing action. In the case of amplifier stages, the effective plate resistance is constant and determines the design of the output apparatus. In a paper published in the "Proceedings of the Institute of Radio Engineers", Vol. 17, pages 1153-1177, July, 1929, I have presented a theory of detection at high signal voltages and have shown that the effective plate resistance is, in the case of the high voltage detector, a variable quantity depending upon the carrier voltage.

The curves of Fig. 2 have been plotted from data obtained by measurement of the effective plate resistance at different carrier voltages, in the case of modulated signals, and for a number of plate voltages. The several solid line curves identified by the reference numerals 160, 180, 55

200 and 220, respectively, show the variations of effective plate resistance for detection with the variation of carrier voltage on the grid. In each instance, the detector was a triode tube of the 5 separate heater type known commercially as a "227 tube", the grid bias being -22.5 volts and the respective plate voltages 160, 180, etc., being indicated by the reference numerals identifying the several curves. The dotted line curve 189a 10 shows the relation between effective plate resistance for detection and carrier voltage when the grid bias was automatically varied as a function of the carrier voltage, the plate voltage being 180 volts.

15 An examination of this series of curves shows that the variation of plate resistance in an ordinary plate-rectifying detector without automatic bias may be considerable, particularly at relatively low plate voltages. This variation may be reduced by increasing the plate voltage, but this has 20 the serious disadvantage of greatly increasing the plate current, which in turn leads to rapid deterioration and failure of the tubes.

In Fig. 3, this variation of the direct current 25 component of the plate current for different carrier voltages is shown graphically, the solid line curve 209F being plotted from data obtained with a fixed grid bias and with 200 volts on the plate, and the dotted curve 209A being plotted from 30 data obtained when the grid bias was automatically varied for the same plate voltage.

This stabilizing action of the automatic bias upon the effective plate resistance for detection permits a rational design of the output load to 35 match an almost steady value of plate resistance with the expectation that the fidelity will remain constant at the various signal levels. It also restricts the dissipation of power by the plate and permits higher operating voltages with attendant 40 higher outputs than would otherwise be possible.

In the detector stage shown in Fig. 4, the operation of the triode D as a plate-circuit rectifier is similar to that of the Fig. 1 circuit, except that the resistance R is shunted by the condenser C in series with a resistance R₁. The 45 input circuit is connected to the junction of R₁ and C, and the resistance R₁ supplements the filter action of the condenser to more effectively prevent the alternating plate currents from being introduced into the grid circuit.

50 In the detector stage of Fig. 5, the screen-grid G² of the tetrode D' is supplied from the plate current source E_b, and the resistance R, shunted by condenser C, is a series element of the screen-grid circuit as well as the input and plate circuits. Since rectification takes place in the screen-grid circuit, the rectifications in both the plate and screen-grid circuits are effective in generating the direct current automatic bias for the 55 control grid G'.

The circuit of Fig. 6 shows a general arrangement of circuits for the tetrode detector D' for 60 individually adjusting the contributions of the effects of rectification in the screen-grid and plate circuits. As in the other circuit arrangements, the resistance R is a series element in the plate circuit but a jumper and an adjustable tap 2 are provided for shunting any desired portion of the resistance. The screen-grid circuit 65 includes the current source E_a and, by means of the adjustable tap 3, may include a portion of the resistance R. The usual radio frequency by-pass condensers C₁ are shunted across those sections of resistance R that are effectively in 70 the screen-grid and plate circuits, and the con-

denser C by-passes audio frequency currents around that part of the resistance R which is included, by adjustable tap 4, in the input circuit. It will be apparent that a detector stage of this type affords wide latitude in the adjustment 5 of the rate at which the automatic bias voltage is varied.

The circuit of Fig. 7 comprises what is, in effect, a special adjustment of the general circuit shown in Fig. 6. In this arrangement, the screen-grid 10 circuit is completed directly to the cathode, and the only rectification effective to vary the control grid bias takes place in the plate circuit.

A second special adjustment is shown in Fig. 8, i. e., the plate circuit is completed to the cathode 15 independently of the resistance R and the rectification in only the screen-grid circuit determines the automatic bias.

The circuit of Fig. 9 represents still another adjustment of the generalized tetrode stage. The 20 rectification in both the screen-grid and the plate circuit establishes a potential drop across the resistance R, but the adjustable tap 4 of the input circuit is so positioned that only a portion 25 of this direct current potential drop is applied as an automatic bias in the control grid G'.

It will be noted that the circuits of Figs. 6 and 9 provide a simultaneous automatic variation of the operating potentials upon both the control and screen-grid circuits since the resistance R is 30 common to both the plate and screen-grid circuits, and the mutual automatic variations of their potentials, particularly that of the screen-grid, is useful in extending the range of linear operation. This extension is due to the automatic 35 lowering of the screen-grid potential as the plate voltage tends to approach it.

The above described circuits for obtaining the automatic bias are especially convenient when the detector tube is of the indirectly-heated type 40 and the operating voltages are derived from an alternating current power line through a rectifier-filter combination. In Fig. 10, I have shown the wiring diagram of a complete radio receiver 45 that includes a detector stage embodying the present invention. Since the amplifier stages are, or may be, of any desired type, they will not be described in detail.

The detector tube D includes a grid G, cathode K and heater coil H. The plate and screen-grid 50 circuits are energized from the voltage divider 5 that is supplied from the rectifier 6 through a filter that includes a series inductance 7 and shunt capacities 3. The low potential side of the rectifier 6 and voltage divider 5 are grounded, 55 but the cathode K of the detector tube is not at ground potential. The resistance R, shunted by the audio frequency by-pass condenser C, is connected between ground and the cathode, and the potential drop across this resistance, due to rectified carrier voltage, is applied to the grid G as an automatic bias.

When it is desired to connect the cathode to a terminal of the input circuit, the radio frequency by-pass condenser C² may be connected as shown 65 in Fig. 11 between the grid and the other terminal of the input circuit, the direct current circuit including the fixed bias source E_c and the automatic bias resistance R being connected between the grid and condenser C². Normally there is 70 no grid detection, but if the applied signal voltages are such as to cause a positive grid current to flow during a part of the cycle there may be some rectification in the grid. If C² is chosen sufficiently large, however, there will be no grid 75

detection but there will be a change in the average grid voltage due to the flow of rectified grid current through R. This method of automatically varying the grid bias is described and claimed in my copending application, and it may be employed to assist the effects of the plate-rectification of carrier voltage. The constants of the circuit of Fig. 11 may therefore be so chosen that the automatic control of the operating characteristics of the tube is obtained by combination of the methods described in this and in my earlier application.

It will be apparent that there is considerable latitude in the design and construction of detector stages, and that the methods herein described may be carried out with arrangements differing from those shown in the accompanying drawings.

I claim:

1. The method of operating a vacuum tube detector of the screen grid type which includes the step of adjusting the polarizing potentials to effect linear detection for a limited range of input voltages, amplifying received signals to bring the detector input voltages to a value not less than those falling within said limited range, and extending the range of input voltages for which linear detection obtains by applying to one element of the tube a bias voltage derived from the rectified current in both the screen grid and anode circuits of the detector.

2. The method of operating a vacuum tube detector of the screen grid type which includes the step of adjusting the polarizing potentials to effect linear detection for a limited range of input voltages, amplifying received signals to bring the detector input voltages to a value not less than those falling within said limited range, and extending the range of input voltages for which linear detection obtains by applying to one circuit of the tube a bias voltage derived from the potential drop established by rectified signal voltage in both the screen grid and anode circuits of the detector.

3. The method of operating a vacuum tube detector of the screen grid type which includes the step of adjusting the polarizing potentials to effect linear detection for a limited range of input voltages, amplifying received signals to bring the detector input voltages to a value not less than those falling within said limited range, and extending the range of input voltages for which linear detection obtains by applying to the control grid a bias voltage determined by the potential drop established by rectified signal voltage in both the screen grid and anode circuits of the detector.

4. In a screen grid detector adapted for linear detection at high signal voltages, the method of stabilizing the plate resistance for detection as the input signal strength varies over a wide range, which method comprises automatically adjusting the control grid bias in accordance with the rectified signal voltage developed in both the screen grid and anode circuits of the detector.

5. In a receiver for carrier wave signals, the combination with a vacuum tube having signal grid, screen grid and anode electrodes, a plurality of electrode circuits, sources of current and impedance elements cooperating therewith to complete the circuits of a transrectifier, and means for amplifying received carrier wave energy to bring the rectifier input voltage to a value not substantially less than that corresponding to linear response of the detector tube, of means in said

screen grid and anode electrode circuits for controlling the direct current operating voltage of the signal grid electrode circuit in accordance with rectified signal voltage in said first electrode circuits.

6. In a receiver for carrier wave signals, the combination with a vacuum tube having signal grid, screen grid and anode electrodes, a plurality of electrode circuits, sources of current and impedance elements cooperating therewith to complete the circuits of a transrectifier, and means for amplifying received carrier wave energy to bring the rectifier input voltage to a value not substantially less than that corresponding to linear response of the detector tube, of an impedance in said screen grid and anode electrode circuits across which rectified signal voltage establishes a potential drop, the signal grid electrode circuit of said tube being so associated with said impedance that the said potential drop automatically controls the direct current operating potential applied to said signal grid electrode circuit.

7. In a detector stage, the combination with a vacuum tube of the screen grid type having input, screen grid and output circuits, of means for extending the range of detector input voltages for which said tube functions as a linear rectifier, said means comprising a resistance common to all said mentioned circuits.

8. The combination of an electric discharge device of the screen grid type provided with a signal grid for controlling the current transmitted between its cathode and anode and that between its cathode and screen grid, means providing screen grid and anode potentials and means for subjecting said signal grid to a bias potential which tends to reduce said currents substantially to zero, said potentials being of such values that said device operates as a bias detector for substantially maximum rectification, means for causing said currents to flow, and means for applying to said signal grid a bias potential controlled by said currents.

9. In the art of rectifying modulated radio-frequency energy by a thermionic detector tube having biasing means common to the input and output circuits thereof, the method which comprises, impressing modulated radio-frequency signal-energy upon the input circuit of said tube, deriving from said radio-frequency energy in the input circuit of the tube by a combination of resistance and capacity solely in the input circuit of the tube a steady negative grid biasing potential, rectifying the signal energy in the anode circuit of said tube to produce variation of the anode current at modulation frequencies, and substantially eliminating by said combination of resistance and capacity variation of the grid potential at modulation frequencies by said variations of anode current in said biasing means.

10. Radio receiving apparatus comprising a detector tube having an input circuit, means for impressing modulated radio-frequency energy upon said input circuit, means for deriving a substantially steady grid biasing potential from said impressed energy comprising an impedance network solely in said input circuit, impedance common to the input and output circuits of said tube, and means for preventing audio-frequency-variations of current traversing said impedance from effecting audio-frequency variation of the potential of the grid of said tube comprising said network.

11. Radio receiving apparatus comprising a detector tube having an input circuit, means for

impressing modulated radio-frequency energy upon said input circuit, a conductive impedance traversed by the anode current of said tube, a conductive impedance of high magnitude connected between the grid and cathode of said tube external to the path of anode current and in series with said impedance and traversed by said impressed radio-frequency energy in the input circuit of said tube, and a condenser of low-impedance to currents of radio-frequency in shunt to said series-connected impedances, said condenser and said second impedance comprising a network for producing a grid biasing potential of magnitude to prevent degeneration by precluding variation of the grid potential at the modulation frequencies of said radio-frequency energy.

12. Radio receiving apparatus comprising a detector tube, a closed loop comprising series-connected conductive impedances and a condenser of low impedance to radio-frequency currents in shunt to said impedances in series, connections from the common terminals of said impedances to the anode of said tube, and connections from the other terminals of said impedances to the grid and cathode of said tube, one of said impedances deriving a grid biasing potential from the anode current of said tube, and the other of said impedances and said condenser deriving a steady grid biasing potential from the input signal energy and preventing variation of the first biasing potential at the modulation frequencies of the rectified signal energy.

13. Radio receiving apparatus comprising a detector tube having an input circuit, means for impressing modulated radio-frequency energy upon said input circuit, a conductive impedance in the anode circuit of said tube traversed by the direct and audio-frequency components of the anode current, a conductive impedance connected between the grid of said tube and the low potential terminal of said first impedance external to the path of anode current, and a condenser connected between the grid of said tube and the high potential terminal of said first impedance, said condenser and said first impedance forming a network whose time constant is greater than the lowest reproduced audio-frequency of anode current for steady grid-biasing purposes, and which prevents degeneration by precluding variation of the grid potential by the audio-frequency variations of anode current traversing said second impedance.

14. Radio receiving apparatus comprising a power detector tube having an input circuit, means for impressing modulated radio-frequency upon said input circuit, a source of anode current, a resistance connected between the cathode of said tube and the negative terminal of said source of anode current, a resistance connected between the grid of said tube and said negative terminal external to the path of anode current, and a condenser connected between the grid and cathode of said tube, said condenser and said second resistance deriving a steady grid biasing potential from the signal energy and preventing the audio-frequency variation of anode current through said first resistance due to plate circuit rectification of said modulated radio-frequency energy from effecting corresponding audio-frequency variation of the grid potential thereby substantially preventing degenerative effects.

15. Radio receiving apparatus comprising a detector tube, a resistance connected between the cathode and anode of said tube, and an input

circuit comprising an inductance having one terminal connected to the grid of said tube and whose other terminal is connected to the cathode and anode terminals of said resistance by a condenser and a second resistance respectively, said condenser and second resistance comprising a network for deriving a steady grid-biasing potential from the radio-frequency signal energy in said input circuit and preventing audio-frequency variations of the anode current traversing said first resistance from effecting corresponding variations of the grid potential.

16. Radio receiving apparatus comprising a detector tube, a resistance connected between the cathode and anode of said tube, and an input circuit tunable to the frequency of modulated radio-frequency energy by variable capacity and comprising an inductance having one terminal connected to the grid of said tube and whose other terminal is connected to the cathode and anode terminals of said resistance by a condenser and a second resistance respectively, said condenser and second resistance comprising a network for deriving a steady grid-biasing potential from the radio-frequency signal energy in said input circuit and preventing audio-frequency variations of the anode current traversing said first resistance from effecting corresponding variations of the grid potential.

17. A receiver comprising a detector tube, a resistance connected between the cathode and anode of said tube, and an input circuit tuned to a radio frequency and comprising an inductance having one terminal connected to the grid of said tube and whose other terminal is connected to the cathode and anode terminals of said resistance by a condenser and a second resistance respectively, said condenser and second resistance comprising a network for deriving a steady grid-biasing potential from the radio-frequency signal energy in said input circuit and preventing audio-frequency variations of the anode current traversing said first resistance from effecting corresponding variations of the grid potential.

18. In radio receiving apparatus, a detector tube having anode, cathode, and grid electrodes, a source of direct-current anode potential, a resistance connected between the negative terminal of said source and said cathode and traversed by the audio frequency and direct current components of the detector anode current, an input element having a terminal connected to the grid of said tube, a condenser of low impedance to radio-frequency currents connecting another terminal of said element to the cathode of said tube, and a second resistance connecting said other terminal of said element to a point of said first resistance removed from cathode to effect negative biasing of the grid, said condenser and second resistance comprising a network for modifying the grid biasing potential and whose time constant is greater than the period of the lowest frequency of said audio frequency component of the anode current.

19. In radio receiving apparatus, a detector tube having anode, cathode, and grid electrodes, a source of direct current anode current, a resistance connected between the negative terminal of said source and said cathode and traversed by the audio frequency and direct current components of the detector anode current, a path in shunt to said resistance including a condenser and a second resistance in series, said condenser and second resistance comprising a network for

varying the grid biasing potential in accordance with signal amplitude and whose time constant is greater than the period of the lowest frequency of said audio frequency component of the anode current, means for impressing modulated radio-frequency energy upon the input-circuit comprising an input element connected from the grid to a point in said shunt path between said condenser and said second resistance.

10 20. The method of preventing slumping of the radio-input audio-output characteristic of a detector tube operating to effect anode circuit rectification, which comprises producing by the anode current a negative biasing voltage applied to the 15 grid of said tube, producing in the grid circuit of said tube, independently of the anode current, a uni-directional current derived from impressed radio-frequency signal energy, and producing by said uni-directional current a voltage of sub-

stantial magnitude, solely in the grid circuit, and supplementing said biasing voltage produced by anode current to increase the negative bias of said grid.

21. Radio receiving apparatus having a detector tube, means for biasing the grid of said tube to effect rectified anode circuit current comprising a resistance included in the grid circuit of said tube and traversed by anode current, a second resistance traversed solely by current in the grid circuit, and a condenser in a path in shunt to a path including said second resistance, said condenser and said second resistance forming a network whose time constant is greater than the period of the lowest frequency of said rectified current and offering low impedance to the radio-frequency input current.

STUART BALLANTINE.
